UNITED STATES PATENT OFFICE.

JAMES N. HEALD, OF WORCESTER, MASSACHUSETTS, ASSIGNOR TO HEALD MACHINE COMPANY, OF WORCESTER, MASSACHUSETTS, A CORPORATION OF MASSACHUSETTS.

GRINDING-MACHINE.

1,285,159.

Specification of Letters Patent. Patented Nov. 19, 1918.

Application filed January 2, 1918. Serial No. 209,824.

To all whom it may concern:

Be it known that I, JAMES N. HEALD, a citizen of the United States, residing at Worcester, in the county of Worcester and 5 State of Massachusetts, have invented a new and useful Grinding-Machine, of which the following is a specification.

This invention relates to a grinding machine, and particularly to improved devices 10 for vertically adjusting the work supporting table. For certain classes of work the range of vertical adjustment required is very limited and at the same time great strength and rigidity in the work supporting structure 15 is essential. Such conditions arise where large numbers of duplicate parts are to be ground, and also where parts are ground upon special fixtures which are designed to substantially correspond with the 20 normal elevation of the table.

It is an object of my invention to provide a grinding machine in which limited but very accurate vertical adjustment of the work table is provided and in which the 25 adjustment is very accurately maintained.

It is a further object of my invention to so arrange the reversing mechanism that the adjustment thereof will remain unchanged when the table is vertically adjusted.

With these objects in view, my invention in its preferred form comprises a lower 30 sliding table having a second or upper table mounted thereon, the two tables having cooperating inclined bearing surfaces, and 35 means being provided for moving the second or upper table longitudinally of the lower table. Such longitudinal movement causes a resultant limited vertical adjustment of the upper table.

The reversing dogs are supported by the upper table and are thus movable longitudinally with the table when the latter is adjusted. The longitudinal relation of the dogs and work is thus unchanged.

My invention further relates to arrangements and combinations of parts hereinafter described and more particularly pointed out in the appended claims.

The preferred form of my invention is 50 shown in the drawings, in which—

Figure 1 is a front elevation of a grinding machine in which my improved work supporting table is embodied;

Fig. 2 is a detail front elevation of a portion of the table, on an enlarged scale;

Fig. 3 is a longitudinal sectional elevation of the work supporting table;

Fig. 4 is a detail horizontal sectional view taken along the line 4—4 in Fig. 2, and

Fig. 5 is a partial sectional elevation taken 60 along the line 5—5 in Fig. 2.

Referring to the drawings, I have shown my invention embodied in an internal grinding machine comprising a base or frame 10 having a head 11 in which is supported the 65 grinding spindle 12 carrying the grinding wheel W. The spindle 12 is eccentrically mounted in a sleeve 13 rotatable in bearings 14 in the head 11. The spindle 12 is driven through belts 15 and 16, and the sleeve 13 70 is driven through a belt 17 and gearing (not shown) from driving shafts mounted in the lower portion of the base 10.

A table 20 is mounted to slide longitudinally in ways or bearings 21 (Fig. 5) 75 formed in the upper surface of the base 10. Suitable devices not shown in detail are provided for moving the table 20 longitudinally, such devices being driven through a shaft 22 and being controlled through 80 speed changing devices 23 and 24 of usual construction.

An inclined bearing surface 25 is formed on the upper side of the table 20, on which surface is supported a second table 26 having 85 a corresponding inclined bearing surface 27 on its lower face. Provision is made for moving the table 26 longitudinally of the table 20, such provision including a nut 28 having a shank portion 29 mounted to 90 slide vertically in a socket 30 in the table 26.

A threaded feed shaft 31 for the nut 28 is mounted in a bearing 32 in the table 20 and is provided with a bevel pinion 33 meshing with a corresponding pinion 34 95 (Fig. 4) on a shaft 35 also mounted in the table 20 and squared at its outer end to receive a wrench or handle. By turning the shaft 35 the table 26 may be moved longitudinally of the table 20 and such movement will cause a resultant vertical adjustment of the table 26. This adjustment, while limited in extent, may be made with extreme accuracy and in every position the table is supported with great rigidity.

If it is necessary to provide for lateral as well as vertical and longitudinal adjustment of the work a cross slide 40 may be mounted to slide transversely on ways formed on the upper surface of the table 26, as best 110

shown in Fig. 3. Lateral adjustment is obtained by the use of the usual cross feed screw 41 coöperating with a nut on the slide 40 (not shown).

5 The longitudinal feed mechanism for the table 20 includes a reversing lever 42 positioned for engagement by dogs 43 and 44 by which the table feed is automatically reversed. Each dog 43 or 44 is mounted upon 10 a stand 45 adjustable longitudinally of the work table. Adjusting screws 46 on the stands 45 provide for close adjustment of the reversing dogs. Instead of mounting the stands 45 in the usual way upon the table 15 20 I provide for them a slide bar 47 supported by arms 48 and 49 extending downward from the table 26 to which they are secured. By this arrangement I am able to adjust the table 26 longitudinally of the table 20 without changing the position of the dogs 43 and 44 relatively to the work supported upon the table 26 or upon the cross slide 40.

Many important advantages are secured 25 by the arrangement of parts above described. I dispense entirely with the use of a vertically adjustable overhanging knee for the table 20 and I support the table 20 upon fixed ways formed directly upon the base 10. Vertical adjustment of the table 26 relative 30 to the table 20 may be made with extreme accuracy, and when once made is securely maintained.

Furthermore, this close vertical adjustment 35 may be made without changing the adjustment of the reversing mechanism. This is an advantage of great importance when grinding to a shoulder, or to the end of a hollow cylinder, and in other similar situations.

Having thus described my invention, it will be evident that changes and modifications can be made therein by those skilled in the art without departing from the spirit and scope of my invention as set forth in the 45 claims, and I do not wish to be otherwise limited to the details herein disclosed, but what I claim is—

1. A grinding machine having, in combination, a frame, a table slidable longitudinally thereon, a second table adjustably mounted on said first table, means to feed said first table longitudinally, and devices mounted on and movable with said second table effective to control said feeding means. 55

2. A grinding machine having, in combination, a frame, a lower table slidable longitudinally thereon, an upper table mounted on said lower table and adjustable on inclined bearing surfaces thereon, means to 60 relatively adjust said tables, feeding and reversing mechanism for said lower table, and feed controlling devices secured to said upper table and movable therewith when said table is adjusted.

3. A grinding machine having, in combination, a frame, a lower table slidable longitudinally thereon, an upper table adjustably mounted on said lower table, feeding and reversing mechanism for said tables, and feed 70 controlling devices secured to said upper table and movable therewith when said table is adjusted, said devices comprising reversing dogs, and a slide bar upon which said dogs are adjustably mounted, said bar being 75 fixed to said upper table and movable therewith.

In testimony whereof I have hereunto affixed my signature.

JAMES N. HEALD.
